FOUNTAIN PEN

Frank M. Ashley, Great Kills, N. Y., assignor to
Lewis Gompers, trustee, New York, N. Y.

Application December 2, 1936, Serial No. 113,812

3 Claims. (Cl. 120—47)

My invention relates to fountain pens for desk use.

The object of my invention is to provide a fountain pen that is of the self filler type, at 5 a low cost.

A further object is to provide a fountain pen in which a piston is used to fill the reservoir of the pen and to form the interior of the reservoir to provide a true cylindrical chamber in which 10 the piston is movable, and to reduce the diameter of the cylinder at its rear end to form an abutment to prevent the removal of the piston from the rear end of the chamber.

A further object is to provide a construction 15 in which the rear end of the piston will be slightly compressed when it reaches the said abutment, to insure a perfectly tight joint between the piston and inner surface of the chamber, regardless of the loose fitting of the piston 20 in said chamber forming the reservoir of the pen.

A further object is to provide a fountain pen 25 in which no separate pen section is required and which is free from threaded joints; also a barrel which is transparent to expose the ink in the reservoir to view.

Referring to the drawing which forms a part of this specification:

Fig. 1 is a longitudinal sectional view thru 30 the fountain pen disclosing my invention.

Fig. 2 is a longitudinal exterior view of the piston and piston-rod.

Fig. 3 is a longitudinal sectional view of the 35 piston, shown on an enlarged scale.

Fig. 4 is a cross sectional view thru the cork 40 ring portion of the piston.

10 indicates the barrel of the pen which is 45 preferably made of transparent or translucent material, and 10' is the reservoir formed therein, and is formed with a smooth cylindrical inner wall 11 which extends from the front end to the point 12 at which place the diameter of the cylinder is slightly reduced to form a tapering abutment into which the cork enters a short 50 distance and is compressed to form a tight joint.

The piston-rod 13 is attached to the rear end 55 of the piston construction which comprises a solid end-piece 14, stem 15, screw 16 and fork 17, the length of the cork extending the full length of the stem and being held thereon in removable relation by the screw 16.

It will be noted that the cork is formed in 60 the shape of a cylinder, and it is impregnated with a composition of soft rubber, indicated by 65 18, which is rolled in fine graphite prior to its setting to provide a flexible coating for the cork which will not stick to the wall of the cylinder in which it moves.

The pen-holder portion 13, referred to as the piston-rod, may be made hollow by the blowing method of manufacture well known to this art, to make the holder as a whole very light in weight, and this portion may be made interchangeable with others of like or different form and color, etc. to match when used in a desk-set. 5

The rear end of the barrel 10 is also tapered at its rear end as illustrated at 19, and at its front end as illustrated at 20. 10

The feed-plug 21 and pen 23 is held in the end of the barrel as shown.

The pen is assembled by first inserting the piston-rod and piston carried thereby, into the front end of the barrel, and thereafter inserting 15 the pen-plug and pen in the open end thereof, as shown.

The pen is filled by a single stroke of the piston in its movement from the front end of the cylinder or ink chamber, to its rear end, after 20 first immersing the front end into the ink, as will be readily understood.

Having thus described my invention I claim as new:

1. In a fountain pen, a barrel having a bore 25 cylindrical for a portion of its length and merging at one end into a tapered bore portion, a feed plug and pen at the other end of the barrel, a piston rod slidable in the bore and projecting outwardly of the tapered end of the 30 barrel, and a compressible cylindrical piston on the inner end of the piston rod adapted to be moved into the tapered end of the barrel.

2. In a fountain pen, a barrel having a bore 35 cylindrical for a portion of its length and merging at one end into a tapered bore portion, a feed plug and pen at the other end of the barrel, a piston rod slidable in the bore and projecting outwardly of the tapered end of the 40 barrel, and a compressible cylindrical piston on the inner end of the piston rod adapted to be moved into the tapered end of the barrel bore and be frictionally retained therein, said compressible piston comprising a cork body having a coating of soft rubber impregnated with 45 graphite.

3. In a fountain pen, a barrel having a bore 50 cylindrical for a portion of its length and merging at one end into a tapered bore portion, a feed plug and pen at the other end of the barrel, a piston rod slidable in the bore and projecting outwardly of the tapered end of the 55 barrel, and a cylindrical piston on the inner end of the piston rod adapted to be moved into frictional engagement with the tapered portion of the barrel bore.

FRANK M. ASHLEY.
